Lloyd I. Volckening, Glen Ridge, N. J., assignor to Ivers-Lee Company, Newark, N. J., a corporation of New Jersey

Application January 21, 1953, Serial No. 23,241

Term of patent 14 years

(Cl. D58—2)

Figure 1 is a front elevational view of a crimp-sealed package or similar article showing my new design, the rear elevational view being the same;

Figure 2 is a side elevational view approximately on the plane of the line 2—2 of Figure 1, the opposite side elevational view being the same;

Figure 3 is an enlarged fragmentary transverse sectional view on the plane of the line 3—3 of Figure 1;

Figure 4 is an enlarged fragmentary transverse sectional view approximately on the plane of the line 4—4 of Figure 1.

I claim:

The ornamental design for a crimp-sealed package or similar article, as shown and described.
